UNITED STATES PATENT OFFICE

AMBROSE H. WHITE, OF BRONXVILLE, NEW YORK, ASSIGNOR TO INTERNATIONAL PAPER COMPANY, A CORPORATION OF NEW YORK

MEANS FOR DRYING BARK OR OTHER SUBSTANCES

Application filed March 11, 1925, Serial No. 14,656. Renewed July 5, 1929.

This invention relates to a method of and means for the treatment of substances or materials to dry the same, and is designed more particularly for the treatment of bark to remove the water which the bark takes up when the latter is separated from the wood in preparing the wood for conversion into pulp in the manufacture of paper.

In accordance with my invention the material to be treated is positively advanced by and between traveling pressure units formed and mounted to subject the material in its travel to a sustained yielding pressure, and the invention consists of the improved apparatus for subjecting the bark to the treatment mentioned, which improvements will be fully described in the specification to follow, and the novel features thereof pointed out in the appended claims.

20 In the accompanying drawings:

Fig. 1 is a side elevation, partly in section, of a mechanism embodying my improvements.

Fig. 2 is a vertical transverse section 25 through the same on the line 2—2 of Fig. 1.

Fig. 3 is a horizontal sectional plan view of the machine on an enlarged scale, certain parts being broken away to better show the construction.

30 Fig. 4 is a plan view partly in section of the frame-structure for supporting and guiding the upper pressure unit.

Fig. 5 is a side elevation of the same.

Fig. 6 is a view in the nature of a diagram, 35 illustrating the operative action of the pressure units on the material under treatment.

Fig. 7 is a diagrammatic view showing how motion is imparted to the operative parts of the machine.

40 Fig. 8 is a fragmentary plan view of the driving shaft and driving sprockets thereon.

Referring to the drawings:

In accordance with my invention, the material A, such as bark with its water content, is, as shown in Fig. 6, fed from a hopper B into the receiving end of a horizontal pressure space or channel C between a lower traveling pressure unit D and an upper traveling pressure unit E which latter unit is 45 yieldingly pressed down by means of springs

F, said units being so formed, as will be described in detail later on, that with the adjacent faces of said units traveling in the same direction, they will act to positively advance the bark, while subjecting the same to a 55 sustained yielding pressure. This will act to effectually squeeze out and remove the water, without injury to the bark, and will deliver the same, substantially free from water, from the discharge end of the pressure space, the 60 water freed from the bark being permitted to escape downwardly and drain off through the lower unit.

The operative parts of the machine embodying the above described essential features, are mounted in and sustained by a main frame consisting of opposing frame members 2, each comprising a lower longitudinal frame bar 3, front and rear upright frame bars 4 and 5, and an upper longitudinal 65 frame bar 6, the two opposing frame members being connected together fixedly in spaced relations by front and rear upper cross frame bars 7 and 8, as best shown in Figs. 1, 2 and 3.

70 The two pressure units D and E before alluded to are mounted between the opposing frame members 2, and each consists of an endless chain of pressure members or shoes, the said units being so mounted one above the other that the lower stretch of the upper chain will be spaced some distance above the upper stretch of the lower chain, thereby forming 75 between them the pressure space or channel C before alluded to.

80 The lower chain of pressure shoes consists of a number of endless carrying chains 9 extending longitudinally of the machine parallel to each other in laterally spaced relations, the adjacent ends of the links of the individual chains being pivotally mounted 85 on and connected together by cross rods 10, which, between the individual chains, have rollers 11 mounted thereon to support the chains in their travel. Transverse plates or 90 bars 12 are bolted or otherwise fixedly fastened to the links of the chains and constitute 95 the pressure members or shoes before alluded to, which bars in the present instance are roughened on their active faces, as by the 100

provision of spurs or spikes 12^a, which are adapted in the travel of the shoes, to take hold of the bark, and in cooperation with similar spurs or spikes on the pressure shoes of the 5 upper unit, advance the bark along the pressure channel.

The rollers 11 on the rods 10 travel on and around a series of longitudinally extending parallel tracks 14 formed, in the present instance, by a series of upright beams consisting 10 each of a vertical web portion 15 and laterally extending edge flanges 15^a, said flanges constituting the tracks 14 above referred to. The said beams are fixedly connected together 15 side by side in spaced relations, by the transverse connecting braces 15^b, and the beams thus connected constitute a supporting frame-structure for sustaining and guiding 20 the endless carrying chains 9 in their travel.

At the ends of the beams the flanges 15^a are curved as shown so as to guide the chains around the ends of the frame-structure, and the latter is mounted fixedly between the opposing 25 frame members 2 by means of front and rear horizontal axles 16 journaled in bearings in the ends of the beams and extending through and supported in bearing openings in the front and rear frame bars 4 and

30 5 near the base of the same. Wheels 17 are fixed to said axles between the outer sides of the outer beams and the inner sides of the frame bars 4 and 5, and these wheels are provided in their peripheries with notches 35 19, in which the ends of the rods 10 of the chains enter, and by which the chains are driven when rotary motion is imparted to the wheels 17 at the front of the machine as will be presently more fully described.

40 The upper chain of pressure shoes constituting the upper pressure unit E is similar in detailed form and construction to that just described, and consists of the individual chains 20, the cross rods 21 to which the 45 links of the chains are pivoted, the rollers 22 carried by the cross rods, and the cross bars 23 fixed to the links of the chain and constituting the pressure shoes. These chains are supported and guided by a frame-structure 50 similar in detailed form and construction to that just described in connection with the lower pressure unit, and consisting of a series of beams 24 provided with edge flanges 25 constituting guiding tracks for the rollers 22. Front and rear horizontal axles 26 are journaled in bearings in the ends of the beams, and wheels 27 are mounted fixedly on 55 said axles at the outer sides of the outer beams, and are formed in their peripheries, similar to the wheels 17, with notches to receive the ends of the rods 21, so that when the wheels 27 at the front end of the machine are rotated in the manner to be presently described, the chain of pressure shoes will at 60 its lower side be caused to travel rearwardly.

This supporting frame-structure for the upper chain of pressure shoes is mounted in the machine frame so that it will be capable of a limited vertical movement, and this for the purpose of enabling the chain of pressure shoes to act with a yielding downward pressure on the material or bark supported by the upper stretch of the lower chain. To effect this object, the axles 26 are mounted in bearing boxes 28 movable vertically in guiding slots 29 formed in the frame bars 4 and 5 near their upper ends, the downward movement of the bearing boxes in the slots being limited by adjustable stop screws 30 at the bottom of the slots. At a number of points in the length of the supporting frame-structure, the outer beams thereof have fixed to them outwardly extending studs 31 carrying on 70 their outer ends, blocks or slides 32 movable vertically in guiding slots in yoke frames 33 pivoted at their lower ends on studs 33^a extending outwardly from the outer beams of the lower frame-structure. The slides 32 are acted on by the springs F before alluded to which bear at their lower ends against the upper sides of the blocks and at 75 their upper ends against heads 34 on the lower ends of screws 35 threaded in the upper ends of the yokes.

It will be understood from the foregoing 80 description that the supporting frame-structure for the upper chain of pressure shoes, is capable of a relative vertical movement in the main frame, and is pressed down with a yielding pressure, the degree of which may be varied by the adjustment of the springs F to meet the varying conditions encountered in practice; and consequently the chain of pressure shoes supported by said frame-structure is capable of like vertical movement, and will act with a yielding pressure on the bark as it is advanced along the pressure space in the travel of the chains.

85 The sides of the pressure space C are closed to prevent the lateral escape of the bark, by 90 means of opposing upper plates 36 fixed to and movable up and down with the upper supporting frame-structure, and lower opposing plates 37 fixed to the lower supporting frame-structure, the adjacent edges of 95 said plates terminating a short distance from each other and leaving an open space between them. This space is bridged and closed by plates 38 adjustably connected to the upper ends of the plates 37, and bearing against the outer sides of the lower ends of the plates 36, all as shown in Figs. 1 and 2. Due to 100 this construction and arrangement of the parts, the opposing upper and lower plates will slide on each other in the up and down movements of the upper chain of pressure shoes, and the plates 38 may be adjusted vertically to meet the varying conditions encountered in practice with respect to the thickness of the pressure space.

The lower chain of pressure shoes is slightly longer than the upper chain so that it will project a short distance beyond the upper chain at the front of the machine, thereby providing a receiving surface 39 at the end of the lower chain onto which the bark or the material to be treated, may be fed from the hopper B before alluded to, which hopper as shown in Fig. 1 discharges onto said receiving surface.

In order to break up any lumps or masses of the bark in the hopper, and to insure its uniform feed to the pressure space between the chains, an agitating and feeding member in the form of a rotary spiked roller 40 fixed to an axle 41^a is journaled in the hopper; and the bottom of the hopper is formed with a roughened or spiked section or plate 41 pressed upwardly by springs 42, which section in cooperation with the roller, will cause the bark to be separated and delivered to the pressure space in the most favorable condition for effective action.

Motion is imparted to the operative parts of the machine, in the present instance, from a short drive shaft 43 as shown in Figs. 7 and 8, mounted in bearings 44 on the main frame at its rear end, the said shaft having fixed to it a driving pulley 45 receiving motion from a suitable source of power. The shaft carries an inner sprocket wheel 46 and an outer sprocket wheel 47; and a sprocket chain 48 passes around the sprocket wheel 46 and around a sprocket wheel 49 fixed on the end of the front axle 26 at the outer side of the front frame bar 4; whereby when the driving shaft is rotated in the direction indicated by the arrow in Fig. 7, rotary motion will be imparted to the front wheels 27, and the upper chain of pressure shoes will be driven with its lower stretch traveling rearwardly. A sprocket chain 50 passes around the outer sprocket wheel 47 on the drive shaft and around a sprocket wheel 51 mounted on a stud 52 projecting outwardly from the side frame bar 4, and this sprocket wheel has fixed to it a spur gear 53 meshing with a spur gear 54 fixed on the end of the front axle 16, whereby the wheels 17 on said axle will be rotated, and the lower chain of pressure shoes will be driven with its upper stretch traveling rearwardly. The relative sizes of the sprocket wheels 49 and 51 are such that the upper chain of pressure shoes will be driven at a higher rate of speed than that of the lower chain, and this in order that the upper pressure shoes will act with a dragging effect on the bark supported by and advancing with the lower pressure shoes, and will thus tend to prevent the mass of bark from packing as it is carried rearwardly.

The spiked roller 40 before alluded to is driven by means of a sprocket chain 55 which passes around a sprocket wheel 56 on the axle 26 at the inner side of the sprocket wheel 49,

and around a sprocket wheel 57 fixed to the projecting end of the axle 40^a of the roller 40.

In the operation of the machine, with the parts driven as described, the bark is fed from the hopper by the action of the roller 40 in cooperation with the spring pressed plate 41, onto the projecting end of the lower chain of pressure shoes, which in its travel rearwardly will carry the bark beneath the upper chain and thus enter it into the receiving end of the pressure channel. In the continued feeding action of the roller 40, and as the chains of pressure shoes travel rearwardly, the bark will be carried along the pressure channel, while being subjected to a pressing and squeezing action by the upper chain of pressure shoes, which squeezing action on the bark is continued and sustained in the travel of the bark throughout the length of the pressure channel. As a result of this action, the water will be squeezed out of the mass of bark, and the latter will issue from the discharge end of the pressure space in substantially dry condition, whence it will be delivered by the lower chain of pressure shoes onto a conveyor 58 by which it will be carried from the machine.

It will be understood that in the foregoing operation, the mass of bark between the adjacent stretches of the two chains is of such thickness that the sliding boxes 28 on the ends of the axles 26 will be sustained free of the stop screws 30, so that the upper chain of pressure shoes will operate with a floating action, while being pressed down yieldingly by the action of the springs F.

Further it will be understood that the degree of pressure with which the chain of pressure shoes acts, may be adjusted and varied by the adjustment of the screws 35; and that by placing the springs F toward the rear end of the chain under a greater tension than the others, the chain of pressure shoes may be caused to act on the bark with increasing pressure as the delivery end of the pressure space is approached.

Having thus described my invention, what I claim is:

1. In a machine of the type described, the combination of a main frame, a lower endless chain of pressure members mounted therein, an upper supporting frame structure, bearing blocks on the opposite sides of said structure at its opposite ends movable up and down in guides in the main frame, adjustable stops mounted on the main frame and supporting said bearing blocks, an upper endless chain of pressure members mounted in said supporting frame structure above said lower chain, slides on the sides of the supporting frame structure movable up and down in guides on the main frame, springs acting on said slides and operating to urge the upper chain of pressure members toward the lower chain, and means for driving the

chains to cause their adjacent stretches to travel in the same direction.

2. In a machine of the type described, the combination of a frame provided with vertical guide slots, a lower supporting frame-structure mounted in said frame, an endless chain of pressure members supported by and traveling around said frame-structure, an upper supporting frame-structure, bearing blocks thereon sliding in the guiding slots in the frame, an upper endless chain of pressure members supported by and traveling around said upper frame-structure, yokes anchored to the lower frame-structure and extending upwardly at the sides of the upper frame-structure, bearing blocks sliding vertically in said yokes and connected to the sides of the upper frame-structure, springs sustained by said yokes and bearing on said blocks, and means for driving the chains to cause their adjacent stretches to travel in the same direction.

3. In a machine of the type described, the combination of a frame provided with vertical guide slots, a lower supporting frame-structure mounted in said frame, an endless chain of pressure members supported by and traveling around said frame-structure, an upper supporting frame-structure, bearing blocks thereon sliding in the guiding slots in the frame, an upper endless chain of pressure members supported by and traveling around said upper frame-structure, yokes anchored to the lower frame-structure and extending upwardly at the sides of the upper frame-structure, bearing blocks sliding vertically in said yokes and connected to the sides of the upper frame-structure, springs sustained by said yokes and bearing on said blocks, means for adjusting said springs independently of each other, and means for driving the chains to cause their adjacent stretches to travel in the same direction.

In testimony whereof, I have affixed my
signature hereto.

AMBROSE H. WHITE.
